UNITED STATES PATENT OFFICE.

ALBERT C. MURPHY, OF NEW YORK, N. Y.

DUMPING-CAR.

1,165,532.

Specification of Letters Patent. Patented Dec. 28, 1915.

Application filed May 6, 1914. Serial No. 836,597.

To all whom it may concern:

Be it known that I, ALBERT C. MURPHY, a citizen of the United States, and resident of New York, county of New York, and State of New York, have invented an Improvement in Dumping-Cars, of which the following is a specification.

The object of my invention is to provide a construction of dumping car in which the body may rock to a tilted position whereby the contents can be discharged to the side of the track and in so doing, guide the dirt or load to the proper distance by use of auxiliary aprons or chute plates suitably supported and brought into operative relation by the tilting act of the body.

My object is, further, to eliminate the severe wear which has heretofore ordinarily come upon the side doors of the body when acting to guide the load being dumped and only employ said doors at time of dumping to prevent objectionable projecting of flying particles or stones, and otherwise insure the proper and most desirable distribution of the dumped contents.

My invention consists of a main frame and a body supported thereon in a manner to be rocked or tilted in a transverse direction, the said body having discharge doors hinged at their upper ends and with their lower ends normally held in closed position by suitable engaging means, auxiliary aprons or chute plates also hinged to the sides of the body adjacent to the floor portions thereof, and automatic means for causing the respective aprons or chute plates to be swung outward to an inclined position according to which side of the body is to be lowered in the act of dumping, the said aprons or chute plates acting to guide the load being dumped to a distance and away from the railroad track; further, in the above devices when associated with means extending to the end of the car for tilting the body and automatically operating means for actuating the engaging means for releasing the doors on the side of the body when being lowered.

My invention also comprehends details of construction which, together with the features above specified, will be better understood by reference to the accompanying drawings, in which:

Figure 1 is a plan view of a dumping car embodying my invention, broken away at the middle to shorten its whole length in

the figure; Fig. 2 is a side elevation of the same and with protecting booths over the end platforms; and Fig. 3 is a transverse section of my improved car, showing the body partly in elevation.

2 is the main frame and is supported at each end by the usual car trucks 3 of any suitable construction. The main frame may be made of girder form and providing a plurality of transverse rocker beds 6. The body 4 is formed of sheet steel and has its under portion provided with rockers 5 which coact with the beds 6 so that the body may rock and tilt in a transverse direction to either side of the main frame, one of the tilted positions being indicated in dotted lines in Fig. 3. This body is furthermore open at its sides and provided with longitudinal metal frames 15, one at each side and forming the upper boundaries of the side discharge openings. The open sides portion of the body are provided with doors 16 which are hinged at 17 to the metal top side frames 15 of the body and adapted to swing outward at the bottom when the body is tilted in dumping the load. Normally these side doors 16 are held in closed position by latches or engaging means 18 which fit over the lower edges of the doors to lock them against outward movement, except at the moment of dumping the load or when the body is in inclined dumping position. These latches or engaging means are preferably automatic in their action and may be made as hereinafter described.

Arranged below each side of the body and hinged thereto at 21 adjacent to the floor thereof, are the aprons or chute plates 20. These plates 20 are moved up and down with the tilting body and in the act of being lowered to the dumping position their free lower ends are swung outward to change the position of the plate from a substantially vertical position to an inclined position, as shown in full and dotted lines in Fig. 3. The means for effecting this swinging adjustment of the plates is the rocking body 4 combined with the pivoted arms 22 and connecting bars 23, the latter hinged at one end to the arms and at the other to the plates 20. The arms 22 are hinged upon the longitudinal shafts 9 and are free to swing thereon in the outward direction but restricted in an inward direction by contacting with the main frame at 24. When the body 4 is in its normal horizontal position

the arms 22 are all forced inward and rest against the parts 2^a of the main frame 2; and in the said position the aprons or chute plates 20 will preferably be slightly inclined outward at the bottom so as to put a thrust upon the arms through the aid of gravity and prevent undue lateral swinging of the plates 20 during the travel of the car.

When the car body is tilted and the discharge side lowered, the apron or chute plate 20 at said side is also lowered; and as its axis of hinging to the body approaches the free end of the arm 22, the radial connecting bar 23 forces the lower and free end of the plate outward into an inclined position, as shown in dotted lines in Fig. 3. While this action is taking place on the descending side of the body, the rising of the other side carries the other apron or chute plate 20 upward and this action pulls upon the bars 23 and causes the free end of the arm 22 to swing around and outward, as shown in dotted lines at the left hand side of Fig. 3. During this operation on the non-dumping side of the body, the door 16 on said side remains locked, which has the advantage of not requiring any attention when the parts are restored to the normal positions.

The rocking of the body 4 may be performed in any suitable manner, the means which I show being hand operated and well suited to the purpose. This means may be described as follows:—A shaft 9 is arranged at each side of the main frame and extends longitudinally of the main frame to a position below each of the end platforms 8 (Figs. 1 and 2). These shafts 9 are journaled in lateral bracket portions 7 of the main frame 2 and are provided with pinions 10 at one or more places. Hinged to the under side of the body and at each side of the rockers are the rack bars 11 which are respectively engaged by the pinions 10 of the respective shafts 9. These rack bars are held up to the pinions by the guide rollers 12. At one end of each shaft is secured a sprocket wheel 13 and at the other end a locking wheel 14^a. These wheels 13 and 14^a are so arranged that one of each comes below each of the platforms 8 as shown in Fig. 1. The sprocket wheels 13 are operated by hand power means 14 which is of a reducing gear order so that a man may operate the shaft 9 which is to tilt the body into dumping position, or vice versa. The locking wheel 14^a is controlled by a locking lever 14^c, so that when the body is to be tilted by the hand power means 14 operating through one shaft 9, said shaft may be unlocked by the lever 14^c at the other end of the shaft. During the normal horizontal position of the body the same may be locked in position during travel by the locking devices 14^a and 14^c at one or both ends of the car. It will be understood that where only one body is em-

ployed on the car it may be operated wholly from one end thereof and one shaft 9 employed, but in practice I prefer to employ the two shafts 9 and the other devices in respect thereto, as shown. Where two shafts 9 are employed, the locking mechanism 14^a and 14^c may be controlled from the same platform from which the body is operated to tilt, the tilting being performed by one shaft 9 and the locking and releasing performed on the other shaft, as indicated in Fig. 1.

I do not restrict myself to any character of means for tilting or rocking the body as that may be done by hand power or otherwise in any of the ways heretofore known and understood by those skilled in the art, the means here shown and described being given by way of example only.

Referring now more particularly to the automatic door releasing mechanism for holding the lower ends of the doors in closed position during transport of the load and for releasing said doors in the act of dumping the load, said mechanism consists of a longitudinal rock shaft 19 at each side of the body 4 and each provided with a plurality of latches or hook-shaped parts 18 which extend upward over the lower edges of the doors 16 to hold them in closed position, said shafts 19 being suitably journaled and adapted to be rocked by arms 25 secured to the shafts and arranged to be operated by links 26. These links 26 are hinged at one end to the free ends of the respective arms 25 of the rock shafts 19 and at the other end are pivoted at 24 to the body 4 with provision for a sliding motion. The rock shafts 19 are arranged in the recess formed by the flanges of the angle irons 15^a constituting the lower side girders of the body. By this arrangement of the rock shafts, the load will not be brought into contact with the shaft or its journal bearings when being discharged. The aprons or chute plates 20 have their hinged supports 21 journaled upon these rock shafts 19, so that the hinges for the said plates 20 are also protected against injury from the discharging contents. When the body is tilted into the dotted position, Fig. 3, the link 26 on the descending side of the body is brought into contact with a portion of one of the lateral extensions 7 of the main frame 2; this arrests the downward movement of the link, while the body tilts somewhat farther and carries with it the rock shaft 19. The effect of this action is to impart a rocking motion to the rock shaft 19 and lower the jaws or latches 18 at a period approximately the termination of the downward movement of the body, thereby releasing the door 16 and allowing the weight of the discharging load to force its way through the door opening and under the door in its released position. During its discharge, the load will pass over

the inclined apron or chute plate 20 which projects or guides it to the proper distance from the track. When the body is again righted to the horizontal position, the various parts will assume their original position shown in solid lines and the doors may be closed and latched, the latching mechanism permitting the necessary movement to enable the doors to be engaged. The weight 10 of the bar 26 acts by gravity to rock the shaft 19 carrying the latches 18 and hence the door 16 may close by gravity and snap back of the latches. I do not restrict myself to the automatic unlatching mechanism here 15 shown, but have described it as a practical construction which I have found well suited for the purpose of releasing the doors automatically at the proper time. Any other suitable door releasing mechanism may be 20 employed.

I have described my invention in the general form which I have found satisfactory in commercial practice, but it will be understood that the various details may be 25 considerably modified without departing from the spirit of the invention.

Having now described my invention, what I claim as new and desire to secure by Letters Patent is:

30 1. In a dumping car, a main frame, combined with a dumping body supported upon and arranged above the main frame and adapted to rock transversely thereon for discharging its load to either side of the main frame, means for rocking the body, doors hinged to the upper parts of the sides of the body and adapted to open by gravity when the body is tilted, automatic means for holding the doors in locked position 35 when the body is horizontal and releasing the doors at the lowered side of the body when tilted, aprons or chute plates hinged to the lower side edges of the body, and means controlled by the tilting of the body to automatically move the apron or chute on the lowered side of the body into an oblique position as the discharging side of the body descends.

2. In a dumping car, a main frame having platforms at its ends, combined with a dumping body supported upon and arranged above the main frame and adapted to rock transversely for discharging to either side of the car, two longitudinal shafts journaled upon the main frame respectively near each lateral side thereof, pinions upon the said longitudinal shafts, racks meshing with the pinions and respectively hinged to the body at opposite sides of its axis of oscillation, separate hand operated means for each of the shafts for imparting rotation thereto arranged at the ends of the main frame and extending above the platforms thereof, automatic doors for discharging the contents from either side of

the body, aprons or chute plates hinged to the lower edges of the body at each side, and means connecting with the respective aprons or chute plates and pivoted adjacent the respective longitudinal shafts whereby 70 said aprons are automatically moved into an oblique outward and downward position, when the edge of the body to which they are hinged is lowered for discharging the load.

75

3. In a car, a main frame, combined with a body supported upon the main frame and arranged to rock transversely, said body having open sides, doors hinged at their upper ends and arranged for normally closing the sides of the body, automatically operated locking means for holding the lower parts of the doors in closed relation but releasing the doors on the discharging side of the body in the act of tilting it, said 80 means comprising a rock shaft at the bottom of the body adjacent to its side and having a plurality of latches and gravity actuated means at the end of the body for rocking the shaft to move the latches into 85 locking position when the body is horizontal and positively moved by contact with the main frame to operate the latches to release the doors when the body is tilted, operating means carried by the main frame 90 extending to one end thereof for tilting the body, and power transmitting devices between the operating means and the body for tilting it.

4. In a car, a main frame, combined with a tilting body supported upon the main frame by means of transverse rockers, said body provided along its upper and bottom side edges with oppositely directed angle irons, doors for the side openings of the 105 body hinged at their upper parts to the outer portions of the upper angle irons of said body, longitudinal shafts respectively arranged on the outer and under portions of the lower angle irons of the body structure, aprons or chute plates at each side of the body hinged to and depending from the respective shafts, latches for locking the doors also carried by the respective shafts, automatic means for rocking the respective shafts when the same are lowered to release the respective doors when being lowered on the dumping side, means for controlling the aprons whereby they are moved into oblique position when lowered 110 with the body in the act of dumping, and means to tilt the body into dumping position.

5. In a car, a main frame, combined with a tilting body supported upon the main 125 frame by means of transverse rockers, means carried by the main frame and having connection with the upper part of the body for tilting it, doors arranged at each side of the body and hinged thereto at the 130

upper ends for automatically permitting the discharge of the contents, hinged aprons or chute plates carried by the body at its sides for guiding the materials being dumped away from the car when the body is tilted, automatic means adjacent to the hinges of the aprons for releasing the doors on the side of the body being lowered whereby they may open by gravity, and automatic devices for swinging the pivoted apron or chute plates outward into an inclined position on the side of the body being lowered.

6. In a dumping vehicle, a main frame supported on wheels, a body supported thereon and adapted to be rocked to discharge to either side of the main frame, doors hinged to the sides of the body and having their lower ends arranged to swing outward, means for rocking the body, chute plates hinged to the sides of the body below the side doors thereof, and means for positioning the chute plates in an outward inclined position on the side of the body when lowered into position for discharging the load whereby the load is guided away from the vehicle when being discharged.

7. In a dumping vehicle, a main frame supported on wheels, a body supported thereon and adapted to be rocked to discharge to either side of the main frame, doors hinged to the sides of the body and having their lower ends arranged to swing outward, means for rocking the body, chute plates hinged to the sides of the body below the side doors thereof, and automatically operating means for positioning the chute plates in an outward inclined position on the sides of the body when lowered into position for discharging the load whereby the load is guided away from the vehicle when being discharged.

8. In a dumping vehicle, a main frame supported on wheels, a body supported thereon and adapted to be rocked to discharge to either side of the main frame, doors hinged to the sides of the body and having their lower ends arranged to swing outward, means for rocking the body, chute plates hinged to the sides of the body below the side doors thereof, means for holding the doors normally in closed position and automatically releasing them when brought to their lowered position by tilting of the body, and automatically operating means for positioning the chute plates in an outward inclined position on the side of the body when lowered into position for discharging the load whereby the load is guided away from the vehicle when being discharged.

9. In a dumping vehicle, the combination of a main frame, a body supported thereon and arranged for rocking transversely thereof, said body having open sides bounded on the top by a longitudinal girder and at the

bottom by a longitudinal angle girder forming a protected channel below the floor of the body, doors hinged to the upper longitudinal girder and closing adjacent to the angle girder, a rock shaft arranged in the protected channel formed by the angle girder, latches or jaws carried by the rock shaft for engaging the doors to lock them in closed position, and means for rocking the rock shaft.

10. In a dumping vehicle, the combination of a main frame, a body supported thereon and arranged for rocking transversely thereof, said body having open sides bounded on the top by a longitudinal girder and at the bottom by a longitudinal angle girder forming a protected channel below the floor of the body, doors hinged to the upper longitudinal girder and closing adjacent to the angle girder, a rock shaft arranged in the protected channel formed by the angle girder, latches or jaws carried by the rock shaft for engaging the doors to lock them in closed position, chute plates hinged to the rock shaft below the doors, means for swinging the chute plates outward into an inclined position when the side of the body to which they are respectively hinged is lowered into dumping position, and means for rocking the rock shaft.

11. In a dumping vehicle, the combination of a main frame on wheels, a body carried thereby and arranged to rock transversely thereon, a door directly hinged at its top to the side of the body and opening by gravity for discharging the load, means for locking the door in closed position and releasing it when brought into dumping position by the body comprising a longitudinal shaft and latches carried thereby, a guiding chute plate jointed to the vehicle and arranged to be moved into outwardly inclined position below the side of the body when dumping its contents, hinged connections between the chute plate and the longitudinal shaft and means for operating the chute plate for automatically positioning it in the act of moving the body into dumping position.

12. In a dumping vehicle, the combination of a main frame on wheels, a body carried thereby and arranged to rock transversely thereon, means to rock the body consisting of longitudinal shafts and power transmitting connections therefrom to the body, doors on the sides of the body and hinged directly thereto at the top of the sides, means for normally holding the doors closed and releasing them when lowered into dumping position whereby they operate by gravity, chute plates hinged to the sides of the body below the doors, and automatic means for moving said chute plates into inclined guiding position to guide the load when being dumped, consisting of arms hinged to the longitudinal shafts of the main frame and

restricted in their rocking movement in an inward direction, and links respectively connecting the free ends of the pivoted arms and the corresponding chute plates to form 5 radius bars for said plates when they are lowered by the body in the act of dumping its load.

In testimony of which invention, I hereunto set my hand.

ALBERT C. MURPHY.
